UNITED STATES PATENT OFFICE.

JOSEPH H. JONES, OF WINTHROP, MASSACHUSETTS, ASSIGNOR OF ONE-HALF TO
ROBERT BURGESS, OF NEWTON CENTER, MASSACHUSETTS.

CAP-SPINNING FRAME.

Application filed July 8, 1922. Serial No. 573,667.

To all whom it may concern:

Be it known that I, JOSEPH H. JONES, a citizen of the United States, residing at Winthrop, in the county of Suffolk, State of Massachusetts, have invented a certain new and useful Improvement in Cap-Spinning Frames, of which the following is a specification, reference being had therein to the accompanying drawings.

- 10 The invention relates to cap-spinning devices of the class in which a cap revolves substantially in unison with an associated spinning element (spindle or bobbin) upon which it is mounted. More specifically, it relates to the so-called pivots, i. e., cap-controlling wheels, which are employed in conjunction with the revolving caps and control the positions of the latter vertically during operation.
- 20 The invention provides a so-called pivot (cap-controlling wheel) having a cap-engaging annulus of suitable frictional material, such for instance as rubber, and also comprising annulus-holding members so contrived and engaged with the said annulus as to prevent the annulus from expanding at high speeds of revolution so as to loosen upon the body of the pivot or throw out in a loop therefrom.
- 30 An illustrative embodiment of the invention is shown in the drawings, in which latter,—

Fig. 1 is a view in side elevation of certain parts of a cap-spinning frame, with 35 certain rails in cross-section, illustrating the connection in which so-called pivots are employed in practice.

Fig. 2 shows the pivot or cap-controlling wheel of Fig. 1, separately, in elevation.

40 Fig. 3 shows the pivot or cap-controlling wheel of Figs. 1 and 2, in vertical section.

Fig. 4 shows the cap-engaging annulus separately in plan.

Fig. 5 shows the said annulus in vertical 45 section in the plane indicated by the line 9, 9 in Fig. 4.

Fig. 6 is a bottom view of the movable securing ring of Figs. 1, 2 and 3.

50 Fig. 7 shows the said movable securing ring in vertical section in the plane indicated by dotted line 7, 7, in Fig. 6.

At 1, Fig. 1, is a portion of the thread-board of a spinning frame, the said thread-board having hinged thereto at 2, in usual

manner, above each spinning spindle, a block 55 3 carrying a guide 4 through which the yarn π that is being spun by the said spindle is controlled and guided between the front rolls and the spindle. At 5 is a spindle rail having mounted thereon in usual manner the 60 bearing-support 6 of the spinning spindle 7, such spindle being in this instance of the well-known sleeve-whirl type and being driven by means of a band 8 encircling the spindle-whirl 71. At 9, is a quill or 65 bobbin mounted upon the spindle blade. At 10 is a revolving cap such as aforesaid, cooperating with the said quill or bobbin 9. At 11, Figs. 1, 2 and 3, is a pivot or cap-controlling wheel coacting with the 70 cap 10; at 12 is a mounting for the pivot or cap-controlling wheel; and at 13 is a supporting rail for the mounting 12.

In the case of devices of the general character shown in Fig. 1, the head of the cap 75 10 has a central hole to accommodate the blade or barrel of the spinning element, in this instance the bobbin 9, with which the cap is combined in operation. The said central hole is proportioned so that the head of 80 the cap has a close but sliding fit upon the said blade or barrel. Such fit, while sufficiently close to permit the cap to be rotated through the engagement with such blade or barrel, nevertheless permits the cap to have 85 vertical movement upon the blade or barrel. The cap gravitates downward until it is supported through its flaring periphery resting upon the cap-contacting peripheral portion of the pivot or cap-controlling wheel 11, as 90 in Fig. 1. The said sliding fit also permits the traverse movements of the cap relative to the blade or barrel which are required to take place for the distribution of the twisted yarn upon the blade or barrel in 95 being wound upon the latter. These traversing movements are due in practice to movements of rail 13 relative to rail 5, or vice versa.

Referring now to the improved construction of pivot or cap-controlling wheel,—

At d is the annulus or ring of frictional material for engagement with the periphery of a cap. It surrounds the body of the pivot 11, as shown best in Fig. 3. In accordance with the invention, the said annulus or ring, the flange e with which the said body is furnished for the support of

the annulus or ring *d* from below, and the securing ring *f* screwing upon the body and engaging with the upper side of the annulus or ring to clamp the annulus or ring in place, are constructed to provide for vertically overlapping engagement between the annulus or ring and the said flange and securing ring. In the present instance, the annulus or ring *d* is formed with upper and lower vertically projecting annular fins or ribs *g*, *g*, Figs. 4 and 5, and the flange *e* and cap *f* have formed therein annular grooves *h* and *i*, Figs. 3, 6, and 7, which are occupied by the said annular fins or ribs when the parts are in assembled relations, as in Fig. 3. It will be perceived that this construction and mode of interengagement in the case of the annulus or ring *d* and the parts between which it is held on the pivot will be effective to prevent the annulus or loop from expanding and bowing out in loop form from the body of the pivot at any speed of rotation of the cap and pivot.

The invention is not restricted to embodiment in the particular specific form, etc., shown in the drawings.

What is claimed as the invention is,

1. The improved pivot or cap-controlling wheel provided with a cap-engaging annulus of frictional material, and with an annulus holding devices clamping said annulus between them, said annulus and holding devices constructed for vertically overlapping engagement between the annulus and the holding means, whereby expansion and looping-out of the annulus under centrifugal action are prevented. 30

2. The improved pivot or cap-controlling wheel comprising the body having a grooved flange *e*, a grooved cap-ring *f*, and an annulus or ring *d* of frictional material formed with projecting rims or ribs occupying said grooves, whereby the annulus or ring is prevented from expanding and bowing out into a loop at high speed. 40

In testimony whereof I affix my signature in presence of two witnesses.

JOSEPH H. JONES.
